METALLIC DOUBLE HUNG WINDOW

Albert Lang, Berkeley, Calif.

Application November 7, 1938, Serial No. 239,216

8 Claims. (Cl. 189—75)

The present invention relates to double hung windows of metallic construction and more particularly to structural improvements in the window frame and sashes and the method of forming same.

One of the objects of the invention is to provide an improved construction for double hung windows and sashes made entirely of metal.

Another object of the invention is to provide a new and improved method of forming window frames and sashes from a continuous metallic strip in a new and novel manner.

Other objects and advantages of the invention will be in part evident to those skilled in the art and in part pointed out hereinafter in connection with the accompanying drawings wherein there is shown by way of illustration and not of limitation a preferred embodiment thereof.

In the drawings:

20 Figure 1 is a perspective view of a double hung window frame and sashes constructed in accordance with the present invention.

Figure 2 is a vertical sectional view taken through Fig. 1 with parts broken out and showing details of construction.

25 Figure 3 is a horizontal sectional view of the frame and sashes taken through the upper sash of Fig. 1.

Figure 4 is a detailed perspective view showing 30 the sealing means employed between the upper and lower sashes of the window frame.

Figure 5 is a fragmentary perspective view showing the window frame forming strip as it is mitred prior to the formation of the frame.

35 Figure 6 is a view similar to Fig. 5 showing the frame forming strip after being bent upon the mitre cut to form a corner of the frame.

Figure 7 is a fragmentary perspective view of a section of the sash forming strip as it is mitred 40 prior to the bending operation.

Figure 8 is a view similar to Fig. 7 showing the sash forming strip after it has been bent to complete the corner of the sash, and

Figure 9 is a fragmentary vertical sectional view showing the manner of up-setting the lower end of the window frame to provide for drainage.

During recent years, there has steadily developed a trend toward the use of various metallic units which can be manufactured at centralized points under factory conditions for dwellings and other buildings. These units have included such elements as various forms of cabinets, ranges and other home facilities which are built into the building at the time of its construction.

55 More recently there has also developed a de-

mand for metallic windows of the double hung type. This latter form of window being particularly preferred over the so-called metallic casement windows that have long been in use on larger structures such as office buildings, hospitals and other public buildings. While these casement windows have found a limited application to dwellings, they have not met with unqualified favor.

As stated hereinbefore, it is a primary object 10 of the present invention to provide a metallic window frame with metallic sashes that can be manufactured with factory facilities and sold as an assembled unit for installation in buildings fabricated of wood, stucco and concrete and 15 which can be produced and sold at a price competitive with the present double hung window frames that are in the main now constructed of wood.

As shown in Figure 1 of the drawings, the window frame and sash contemplated by the present invention comprises an outer frame 10 of channel-like construction having parallel outwardly extending side walls 11 and 12 which respectively form the inside and outside faces of the head, 25 jambs and sill of the window frame. In its formation the frame 10, as will hereinafter appear, is provided with an inwardly disposed rib or flange portion 13 which, in conjunction with a removable channel-like parting strip 14, provides 30 a guide means for the lower sash designated by the numeral 15. The respective flanges of the strip 14 form a parting bead 17 and a relatively spaced outer window stop 18 which cooperate to provide a guide means for the upper sash. The 35 upper sash designated by the numeral 16 as illustrated is then disposed between the outer sash stop 18 and parting bead 17 of the channel-like member 14 and is guided thereby in its upward and downward movements. In addition to the window frame 10 and the sashes 15 and 16 which are constructed entirely of metal in a new and novel manner as will hereinafter appear, the frame 10 and the sashes 15 and 16 are adapted to be provided with any suitable form of sash balancing means, which means as will be understood may be concealed within the channel formed between the side wall forming flanges 11 and 12 of the frame 10 when the frame is installed in the wall of a building.

Upon referring to Figures 2 and 3 of the drawings, it will be noted that the inwardly disposed rib or flange portion 13 of the frame 10 extends perpendicularly and inwardly from the inner or light opening defining wall or web 10a of the 55

frame 10 and is disposed at the room side of the frame adjacent the inside flange 11 thereof where the lower sash 15 may be positioned thereagainst. It will also be noted that the parting bead 17, in addition to retaining the lower sash 15 against the inner window or sash stop 13 of the frame 10, will serve to also space and position the upper sash 16 with respect to the lower sash 15. At the outside of the upper sash 16 the channel-like parting strip 14 is shown as provided with the outer window or sash stop 18 that serves in conjunction with the parting bead 17 to provide guides between which the upper sash 16 moves. Thus the inner sash stop 13 and the parting bead 17 define an inner sash groove while said parting bead 17 and the outer sash stop 18 define an outer sash groove. The channel-like parting strip 14 is here illustrated as secured upon the inside surface of the head and jambs of the window frame 10 by means of screws 19. It will be understood, however, that this member 14 may be secured upon the frame 10 in any other suitable manner, as for example, by spot welding after the sashes 15 and 16 have been positioned within the frame 10. The use of screws 19, however, is to be preferred as it provides a convenient means for removing the sashes should this become necessary after the window frame has been installed in the wall of a building.

30 As a further novel feature of the present invention, the window frame 10 is shown as having outwardly extending ribs 20 and 21 formed respectively upon the inside and outside walls 11 and 12 of the main channel-like section. The rib 20 upon the inside face of the frame 10 is produced by forming an outwardly extending channel in the inside of the side wall 11 of the window frame 10 and preferably this rib forming channel or plaster stop is of relatively narrow width. In fact, it is conceivable that the rib 20 might be provided by merely forming an outwardly extending fold in the wall 11 of the frame 10. The purpose of this rib 20 is to provide a molding to which the plaster will extend when applied to the interior wall of the building, the purpose being to provide a neat finish between the frame and the interior surface of the wall in which the frame 10 is inserted. The rib 21 at the outer side of the frame 10 is formed in the wall 12 of the channel-like section in a similar manner but in this instance this rib is made of considerably larger dimensions so as to conform with the finished siding of the building whether it be clapboard, stucco or concrete. At this point it should be noted that the ribs 20 and 21 extend entirely around the frame 10 and respectively over the inside and outside surfaces of the head, jambs and sill of the frame and as a result the window frame 10 may be said to have a uniform configuration of cross-section in its head, jambs and sill forming portions. As a result the frame 10 is adapted, as will hereinafter appear, to be fabricated from a single continuous strip of sheet metal in a new and novel manner.

65 It will also be noted that the ribs 20 and 21 form rabbets 20a and 21a on both the interior and exterior sides of the frame, which rabbets are adapted to receive screen frames or the like.

In addition to providing a novel and inexpensive outer window frame, the present invention also contemplates the provision of a new and novel form of sash frame which possesses characteristics similar to those embodied in the window frame 10 and which therefore also makes possible the formation of both the window frame 10 and the sash frame 15 and 16 in accordance with a similar method of manufacture. As shown, the frames of the sashes 15 and 16 are of uniform and similar configuration and cross-section around their tops, sides and bottom portions. It will also be noted that the sash frames like the window frame 10 are of a channel-like cross-section having an inner light opening defining wall 22 and two spaced parallel outwardly extending flanges 23 and 24 that provide respectively inside 10 and outside surfaces of the sash frames. These sash frames, like the window frame 10, are also provided with a smaller inwardly disposed channel forming portion 25 that forms a cleat against which glazing glass, designated by the numeral 15 26, may be secured in the conventional manner by the application of putty 27. At the outer edge of the sash frames the side walls 23 and 24 are provided with inwardly extending and aligned flanges 28 that define the outer surface of the sash frames. These flanges 28, as will herein-after appear, in connection with the method of manufacture are comparable to the aligned walls of the channels which form the plaster stops 20 and 21 upon the frame 10 so that during the fabrication of the frame these portions form a bending connection between the top, sides and bottom of both the frame 10 and the sashes 15 and 16 and, therefore, provide a double hung window frame and sashes therefor which can be manufactured by a similar and novel method of procedure.

Before proceeding with a description of the method provided for forming the frame 10 and the sashes 15 and 16 of the above described character, attention is directed to Figure 4 of the drawings wherein a further detail in the construction of the upper and lower sashes 15 and 16 is illustrated. In this figure of the drawings, 35 29 designates a right angled member having an outwardly disposed right angled flange 30 which cooperates with a similarly disposed flange 31 formed upon a second right angled member 32 that is similar in every respect to the right angled member 29. As shown in Figure 2 of the drawings, the right angled member 29 is adapted to be secured along the top or meeting rail of the lower sash 15 with its flange 30 extending downwardly and the right angled member 32 is adapted to be secured to the bottom or meeting rail of the upper sash 16 so that its flange 31 will interlock or overlap with the flange 30 upon the member 29. These members 29 and 32 are here shown as having an offset outer edge 33 that is adapted to be disposed under the outermost inwardly extending flange of the sash frames 15 and 16. 45

In order to provide a weather tight seal between the overlapping flanges 30 and 31 of the members 29 and 32, the flange 30 is shown as provided with an upwardly and diagonally extending flexible weatherstrip 34. This weatherstrip 34 may be of any suitable material. For example, it may be of rubber, but it is preferably formed from a relatively thin strip of bronze. As shown, the weatherstrip 34 is crimped around 50 the edge of the flange 30 as at 35 and extends upwardly and outwardly in such a manner that it will be engaged by the flange 31 when the meeting rails of the sashes 15 and 16 are brought into alignment. With this arrangement it will be readily seen that when the sashes 15 and 16 are in their closed positions upon the frame 10 the window opening will be completely closed. In this connection it should be stated that while Figures 2 and 3 of the drawings show the sashes 55

15 and 16 as spaced somewhat from their respective guides, this dimension will be reduced to a substantially sliding fit when the sashes are properly mounted upon the frame 10. As an additional adjunct it is conceivable that the open sides and ends of the sashes may be closed if desired throughout their entire periphery by an additional closing member which may be spot welded or otherwise secured to the oppositely disposed flanges 28 at the outer edges of the sash frames. These additional frame closing members will cooperate with the members 29 and 32 to provide a continuous outer surface about the sashes 15 and 16. The use of such a member on the sides of sashes 15 and 16, however, is not in any way necessary as these sides of the sashes are concealed and protected against the weather by the frame 10 and the sash guides provided thereupon. In fact, it would be preferable where the use of screws 19 is relied upon to secure the channel forming member 14 upon the frame 10 to omit such a frame channel closing member and thus provide a clearance over the heads of the screws 19 that are relied upon to secure the channel member 14 to the window frame 10.

Reference is now made to Figures 5 and 6 of the drawings for the purpose of describing the novel method by which the double hung window frame is fabricated from a single continuous strip of sheet metal. As illustrated in Fig. 5 and as has been stated above, the strip from which the frame 10 is constructed is rolled as one piece from a continuous flat strip of sheet metal into a substantially channel-like configuration with the cleat forming portion 13 extending outwardly from the bottom of said channel configuration and with the plaster stops 20 and 21 formed respectively on the inside and outside walls 11 and 12 of the finished frame. After the strip has thus been rolled it is passed through a mitre cutting machine where a mitre cut 35 will be formed laterally therethrough with the apex of the mitre cut 35 positioned just inside of the aligned side walls of the plaster stops 20 and 21. As here shown it is the outer walls designated respectively by the numerals 36 and 37 of the plaster stops 20 and 21 that are aligned and uncut by the mitre 35. It will be understood that the mitre cuts 35 will be located along the pre-formed strip at properly spaced points so as to provide for an alternate location of the head, jambs, and sill of the finished frame and that the ends of the strip when thus cut to provide the four sides of the frame will be mitred at its ends so as to provide a joint between the meeting ends of the strip after the strip is bent into rectangular form to complete the frame.

When the strip has thus been mitred and bent as illustrated in Fig. 6, the bending thereof will take place in the outer walls 36 and 37 of the plaster stops 20 and 21. These uncut portions of the strip forming what might be termed hinges between the adjacent portions of the strip. With this arrangement it will be seen that the uncut side walls 36 and 37 of the plaster stops 20 and 21, because of their alignment and lateral spacing, will function to exactly position the mitred portion of the channel-like strip so as to bring the inner meeting walls of the main channel section into exact alignment. At this point it may be said that during this bending operation the small outwardly extending portion of the side walls 11 and 12 will be confined in the bending machine so as to prevent any undesirable deflection thereof during the bending operation. In other words,

these portions of the side walls which extend outwardly beyond the uncut portions of the plaster stops 20 and 21 will be stretched in a manner well understood in the art. At the same time the outer walls 36 and 37 of the plaster stops 20 and 21 will retain their proper right angled alignment and provide an uninterrupted wall against which the plaster is placed. As a final step to complete the frame and reinforce the corners, the invention contemplates the insertion of a right angled member 38 in the channel that forms the cleat 13 upon the face of the head, jambs and sill of the finished frame. The member 38 is constructed of such dimensions that it will extend around the corners and fit snugly 15 into the channel described where it may be spot welded or otherwise secured in place. While it is conceivable that the right angled member 38, because of its inward disposition from the uncut portions in the side walls 11 and 12 of the frame 20 may be sufficient for all practical purposes, it is contemplated that an additional securing means in the form of another right angled strip 39 may if desired be secured to the inside surface of the light opening defining wall of the channel-like 25 section. Instead of this latter right angled member 39, it is also conceivable that a right angled member 40 similar to the construction of the member 38 may be pressed in and secured within the channel that forms the plaster stop 21 in 30 the wall 12 of the finished frame. In practice it will be understood that the choice of the securing and reinforcing means 38, 39 and 40 will be dictated by the nature and size of the frame to be constructed. In larger frames it is possible 35 that all three securing and reinforcing means may be resorted to but in smaller frames it is possible that any one or two of these securing and reinforcing means 38, 39 and 40 may be sufficient.

Reference is now made to Figures 7 and 8 of the drawings for a further description of the herein disclosed method of manufacture as it pertains to the construction of the sash frames. As illustrated in Fig. 7, the strip from which the sash frames 15 and 16 are formed is rolled to form a channel-like configuration having side walls 23 and 24 with the small channel 25 at one side thereof to form the cleat 26 against which the glazing glass is secured. At the outer edges 45 of the side walls 23 and 24 of the channel these walls are bent inwardly so as to provide aligned oppositely disposed flanges 28. After the strip has been thus formed it is passed through the mitre cutting machine and is provided with 55 mitre cuts 41 at points therealong which will correspond to the corners of a finished sash frame. As shown, the mitre cut 41 extends through the cleat forming channel 25 and the light opening defining wall 22 of the strip to a 60 point corresponding to the inside surface of the oppositely disposed flanges 28. After the sash forming strip has thus been rolled and mitred, the mitre cuts 41 are closed by bending the strip on the uncut oppositely disposed flanges 28 so 65 as to bring the adjacent sides of the frame into aligned relation as illustrated in Fig. 8 of the drawings. With this arrangement it will be noted that the oppositely disposed flanges 28 operate in identically the same manner as do the uncut 70 walls 36 and 37 of the plaster stops 20 and 21 of the main sash frame 10, and as a result the meeting edges of the sash frame at the mitre cuts 41 will be brought into exact alignment as the corner is thus formed. After the strip has been 75

bent as illustrated in Fig. 8 to complete the corners thereof a securing and reinforcing member 42 will be forced into and secured in the channel 25 that forms the cleat 26. This reinforcing member 42 like the reinforcing member 38 on the window frame 10 will be dimensioned so as to fit snugly into the channel 25 after which it may be secured in place by spot welding and/or other suitable means. As a further similarity between the sash forming frames and the window frame it will be noted that the flanges 28 like the uncut walls 36 and 37 of the plaster stops 20 and 21 upon the window frame are oppositely disposed in alignment and project inwardly toward each other. The sashes 15 and 16 like the window frame 10 are also completed by providing the ends of the sash forming strip with mitred ends which when brought into alignment can be secured together in the manner above described to complete the sash frame.

Reference is now made to Figure 9 of the drawings. As will be apparent from the above, the double hung window frame 10 unlike all other metallic double hung window frames of the prior art, is constructed from a single pre-formed strip of sheet metal and therefore the head, jambs and sill thereof when completed will be of the same configuration. In order to provide for drainage at the sill, the present invention also contemplates a slight upsetting of the light opening defining wall in the sill forming portion of the frame. This is accomplished as illustrated in this figure of the drawings by subjecting the light opening defining wall of the sill, designated by the numeral 43, to an inward pressure which will deflect this wall of the frame inwardly to provide a slight outward slope from the cleat 13 to the outer wall 12 of the finished frame. In forming this deflection it will be seen that the inner wall, designated by the numeral 44, of the channel which forms the cleat 13 will be upset as at 45 to permit this deflection of the wall 43 which forms the sill. It will be understood that the amount of this deflection in the wall 43 will needs be only sufficient to provide for drainage. For example, an upsetting in the amount of one-eighth to one-quarter inch in a frame of the character described will be sufficient for all practical purposes.

While I have, for the sake of clearness and in order to disclose the invention so that the same can be readily understood, described and illustrated specific devices and arrangements, I desire to have it understood that this invention is not limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is—

1. A metallic frame for double hung windows comprising a strip of sheet metal formed of uniform cross-section throughout and with an inner connecting web to define a light opening and having parallel outwardly extending spaced sides forming the inside and outside of the frame, said outwardly extending parallel sides having flanged portions near their outer edges disposed in alignment with each other on a line extending parallel to the connecting web of the frame, said frame being formed by providing a mitre cut 76 at points corresponding to the corners which ex-

tends through said connecting web and into said outwardly extending parallel sides to the inside surface of said aligned flanged portions and being bent on said flanged portions to form the corners thereof.

2. A metal frame for double hung windows comprising a continuous strip of sheet metal formed of uniform cross-section throughout and with an inner connecting web to define a light opening and having parallel outwardly extending sides at each end of said inner connecting web forming the side walls of a channel about the frame, each of said outwardly extending parallel sides having outwardly disposed channel forming portions to form plaster stops upon the inside and outside surfaces of the frame, said plaster stops being aligned with respect to each other so that at least one side wall of each channel forming portion will be in alignment with a side wall of the opposite plaster stop and along a line extending parallel with the inner connecting web of the frame, said frame being formed by providing a mitre cut at points corresponding to the corners of the frame which extends through the inner connecting web and into said parallel sides to the aligned side walls of said plaster stops, whereby the sides and inner connecting web of the frame will be held in alignment by the uncut side walls of the plaster stops when the frame is formed.

3. A sheet metal frame for double hung windows comprising sill, jamb and head portions of uniform channel-like cross-section throughout and providing relatively spaced side walls forming the inside and outside faces of the frame, an inner web connecting the inner edges of said side walls and defining a light opening, and an inner flange circumscribing said light opening and projecting perpendicularly from said connecting web, a parting bead on the jamb and head portions of said connecting web spaced from said inner 40 perpendicular flange to define an inner sash groove, and an outer window stop on said jamb and head portions of said connecting web spaced from said parting bead to define an outer sash groove.

4. A sheet metal frame for double hung windows comprising sill, jamb and head portions of uniform channel-like cross-section throughout and providing relatively spaced side walls forming the inside and outside faces of the frame, an inner web connecting the inner edges of said side walls and defining a light opening, and an inner flange circumscribing said light opening and projecting perpendicularly from said connecting web, and a channel-like parting strip on 55 the jamb and head portions of said connecting web having an inner flange formed to provide a parting bead spaced from said inner perpendicular flange to define an inner sash groove and an outer flange formed to provide an outer window 60 stop spaced from said parting bead to define an outer sash groove.

5. A sheet metal frame for double hung windows comprising sill, jamb and head portions of uniform channel-like cross-section throughout 65 and providing relatively spaced side walls forming the inside and outside faces of the frame, an inner web connecting the inner edges of said side walls and defining a light opening, and an inner flange circumscribing said light opening 70 and projecting perpendicularly from said connecting web, a parting strip of channel form adapted to be positioned on the jamb and head 75 portions of said connecting web and formed to

provide a parting bead and an outer window stop spaced therefrom to define an outer sash groove, said parting strip being insertable in said light opening from the outer or weather side of the frame to position said parting bead in spaced relationship relative to said perpendicular inner flange to define therewith an inner sash groove, and means for securing said parting strip in such position. 5

6. A window frame unit including sill, jamb and head portions comprising a strip of sheet metal of uniform channel-like cross-section throughout and providing relatively spaced side walls forming the inside and outside faces of said frame unit, an inner web connecting the inner edges of said side walls and defining a light opening, and an inner flange circumscribing said light opening and projecting perpendicularly from said connecting web to form a window stop, each side wall being formed to provide a channel-like rib outwardly disposed perpendicular thereto to form therewith a rabbet adapted to receive a screen frame or the like. 10

15 7. A window frame unit including sill, jamb and head portions comprising a strip of sheet metal of uniform channel-like cross-section throughout and providing relatively spaced side walls forming the inside and outside faces of said frame unit, an inner web connecting the inner edges of said side walls and defining a light opening, and an inner flange circumscribing said light opening and projecting perpendicularly from said connecting web to form a window stop, each side wall being formed to provide a channel-like rib outwardly disposed perpendicular thereto to form therewith a rabbet adapted to receive a screen frame or the like, the outside perpendicular wall of both of said ribs being in alignment and parallel with said light opening defining web, said unit being formed by providing mitre cuts at points corresponding to the corners thereof extending through said connecting web and into said side walls to leave outer uncut portions and being bent on said uncut portions to form said corners. 20

25 8. A window frame unit including sill, jamb and head portions comprising a strip of sheet metal of uniform channel-like cross-section throughout and providing relatively spaced side walls forming the inside and outside faces of said frame unit, an inner web connecting the in-

ner edges of said side walls and defining a light opening, and an inner flange circumscribing said light opening and projecting perpendicularly from said connecting web to form a window stop, each side wall being formed to provide a rib outwardly disposed perpendicular thereto to form therewith a rabbet adapted to receive a screen frame or the like. 15

20 9. A window frame unit including sill, jamb and head portions comprising a strip of sheet metal of uniform channel-like cross-section throughout and providing relatively spaced side walls forming the inside and outside faces of said frame unit, an inner web connecting the inner edges of said side walls and defining a light opening, and an inner flange circumscribing said light opening and projecting perpendicularly from said connecting web to form a window stop, each side wall being formed to provide a channel-like rib outwardly disposed perpendicular thereto to form therewith a rabbet adapted to receive a screen frame or the like, the outside perpendicular wall of both of said ribs being in alignment and parallel with said light opening defining web, said unit being formed by providing mitre cuts at points corresponding to the corners thereof extending through said connecting web and into said side walls to leave outer uncut portions and being bent on said uncut portions to form said corners. 25
